UNITED STATES PATENT OFFICE.

WILLOUGHBY L. T. HAIN, OF PHILADELPHIA, PENNSYLVANIA.

VENDING MACHINE.

Application filed July 15, 1921. Serial No. 434,878.

To all whom it may concern:

Be it known that I, WILLOUGHBY L. T. HAIN, a citizen of the United States, residing at Philadelphia, in the county of Philadelphia and State of Pennsylvania, have invented certain new and useful Improvements in Vending Machines, of which the following is a specification.

The invention relates to coin controlled vending machines.

The primary object of the invention is to provide a device of the character stated that will only operate to deliver a chewing gum or candy ball to the operator, when a coin of the denomination of a cent or penny is deposited therein; the novel construction of the device being of such a character that after the coin is secured therein the machine must deliver the ball to the operator, yet said machine cannot be so manipulated by said operator as to cause more than one ball to be delivered for the one coin.

This object and other advantageous ends, I attain by means of the mechanism herein-after described, reference to be had to the accompanying drawings, forming a part hereof, in which:—

Figure 1 is a sectional side elevational view of the device, illustrating the carrier at the completion of its travel;

Figure 2 is a sectional plan view on line 2—2 of Fig. 1, illustrating the carrier in its normal position;

Figure 3 is a sectional plan view on line 3—3 of Fig. 1, illustrating the carrier at the completion of its travel;

Figure 4 is a sectional plan view on line 4—4 of Fig. 1, illustrating the carrier on its return travel;

Figure 5 is a sectional side view illustrating the carrier in its normal position;

Figure 6 is a transverse sectional view on line 6—6 of Fig. 2;

Figure 7 is a vertical sectional view on line 7—7 of Fig. 1, and

Figure 8 is a front sectional elevational view on line 8—8 of Fig. 1.

Referring now more particularly to the several figures of the drawing wherein similar reference numerals indicate like parts in all of the views, the device comprises essentially a suitable hollow base 10 in the form, substantially, of an inverted bowl preferably constructed of aluminum with a flat top 10', a hollow annular body portion 11 having the outwardly projecting lip 12,

as illustrated, a separable plate or disc 13 thereover, an integral lip 14 on said plate 13 extending over the lip 12 and a glass container 15 secured on said plate 13 in 60 the manner hereinafter described.

Long threaded screws 16—16 extend downwardly through communicating openings in the plate 13, body portion 11 and the top portion 10' of the base 10. Nuts 17 65 —17 are threaded on said screws 16—16 beneath and against the underside of the top portion 10' of the base 10 to secure said body portion 11 and the plate 13 thereover, firmly in position on the said top portion 10'. 70

An integral transverse partition 18 is provided substantially centrally in the body portion 11. Upwardly projecting guide rails 19—19 extend longitudinally on the upper surface of the said partition 18. A cam 75 lever 20 is pivoted on a stub shaft 21 extending transversely of the lip 12 and rigidly secured in corresponding openings through either side of the said lip 12. A vertical slot 22 is provided substantially 80 through the centre of the lip 12 for the play of the said lever 20.

A spiral spring 23 is mounted on the shaft 21 and is operatively connected with said lever 20 to return said lever 20 to its original position after use thereof. A substantially rectangular opening 24 is provided in the forward portion of the partition 18 and extends partially beneath the lip 12 and is slotted as at 25 to permit of the free end of 90 the lever 20 to normally rest therein and against the inner front wall of the lip 12 below the slot 22.

A separable member 26, in the nature of a carrier, is adapted for longitudinal movement on the partition 18 between the guide rails 19—19. A boss 27 is provided on the under forward portion of the carrier 26 and extends substantially the length of the rectangular opening 24. Said boss 27 is slotted longitudinally as at 28, (Fig. 1) and has the downwardly projecting integral lugs 29—30 on either side of said slot 28 preventing lateral displacement from the opening 24 and providing a vertical support for the 100 coin 60 thereagainst. One side of the boss 27, alongside of the lug 29, is cut away to provide for positioning a ratchet 31 therebeside. The said ratchet 31 is notched as at 32 at its outer terminus to normally engage 110 the end of the lug 29. The said ratchet 31 is mounted for lateral movement across the

rectangular opening 24 beneath the carrier 26, on the shank of a screw 33 threaded into an opening in the partition 18 as shown in detail in Fig. 1.

5 A leaf spring 34 (Fig. 4) is secured to the outer side of the ratchet 31, the free end thereof being in contact with one of the inner side walls of the lip 12 and is adapted for compression between said wall and the 10 lug 29.

A transverse coin slot 36 is provided in the forward portion of the carrier 26 and normally communicates with a similar slot 37 in the lip 14 of the plate 13 and a slot 38 15 in the under portion of the lip 12. The opposite end of the carrier 26 has an annular opening 39 which when the carrier completes its forward travel communicates with a like opening 40 in the partition 18 permitting a ball 65 to enter a chute 41 in the base 10, said chute 41 leading to an opening 42 in the front portion of the base 10 whereby the said ball is delivered to the operator of the device.

25 Tubes 43—43 are loosely positioned around the screws 16—16 between the partition 18 and the under side of the plate 13. A leaf spring 44 (Figs. 3 and 4) is positioned against the tubes 43—43 and passes 30 through a slot 45 in the under portion of the carrier 26, so that said spring 44 is compressed against said tubes 43—43 by the forward travel of the carrier 26. These tubes 43—43 act as roller bearings for said 35 spring 44.

The cam lever 20 is provided with a thumb latch 46 and has the cam portion 47 in the form, substantially, of a boot (vide Figs. 1 and 5). Said lever 20 to prevent wear by 40 friction is preferably constructed of manganese bronze.

A ratchet 48 is pivoted on a stud 48' (Fig. 4) on the partition 18, as shown, and is adapted to engage ratchet teeth 49 provided on the side of the boss 27 on the carrier 26. A tension spring 50 is operatively connected to said ratchet 48, the other extremity of said spring 50 being secured around a stud 51 adjacent to the stud 48' on 50 the said partition 18.

The glass container 15, of such contour and dimensions as may be found requisite, is secured on the plate 13 in manner following, viz: The plate 13 has an annular groove 52 on its upper surface, a suitable washer 53 is positioned in said groove 52 and the container is positioned on said washer. An annular ring 35 is positioned in the open upper portion of the container 15. A U shaped member 56 depends from said ring 35 within the said container 15. The long screws 16—16, heretofore described, above the plate 13 terminate in heads 16'—16' having integral eyelets 16"—16" (Fig. 8). A yoke 57, the 60 free ends of the arms of which are turned

outwardly to form hooks 57'—57' are hooked in the said eyelets 16"—16". A threaded member 58 extends vertically from the top of the yoke 57 through an opening in the U shaped member 56. A finger nut 59 is 70 threaded downwardly on the member 56 firmly positioning the container 15 on the plates 13, the arms of the yoke 57 being more or less resilient. The nut 59 is to be threaded against the member 56 by means of the fingers, obviating the possibility of breaking the container 15 in securing same in position, which is always present when a screw driver is used to secure said container 15 in position.

In lieu of the heads of the screws 16—16 being provided with the eyelets 16"—16", said screw 16—16 may terminate in the usual flat screw heads and suitable eyelets may be cast or otherwise secured on the plate 13.

85 A suitable cap or cover 54, having the finger grip 55 is secured over the upper open end of the container 15 in any suitable manner.

The bottom portion 67 of the base 10 may 90 be hinged as at 66 and suitable locking means provided at 68.

In operation: a coin 60 is placed in the slot 37 in the lip 14 of the plate 13 and passes 95 down through the transverse coin slot 36 in the boss 27 on the carrier 26. These slots are of such a dimension that only a coin of the denomination of a cent or penny can be operatively employed therein. The said coin 60 is stopped by and rests against the inner side of the ratchet 31 which is under compression by the spring 34, said ratchet 31 preventing the escape of the coin 60 through the slot 38 in the under portion of the lip 12.

The thumb latch 46 of the cam lever 20 is forced downwardly causing the cam portion 47 thereof to contact against the coin 60 forcing said coin in a depression or shoulder 63 in the under forward upper portion 100 of the carrier 26. The coin 60 is now secured so that it cannot be taken out by the operator of the device nor can it be retrieved by means of a piece of wire inserted in the slots 36 and 37 as is sometimes done in the usual type of this kind of a device. Further 105 this action permits of further pressure against the coin 60 by the cam 47 without forcing said coin vertically through the slot 37.

110 As the carrier 26 continues its forward travel by means of the pressure of the cam 47 against said coin 60, the said coin 60 moves forward with the carrier 26 by reason of 115 said coin being held against the lugs 29 and 30, forcing the ratchet 31 outwardly and whereby the notched end 32 of said ratchet 31 is forced out of engagement with the end of the lug 29, until said coin 60, by the forward travel of the carrier 26, reaches a recess 61 in said ratchet 31, which said recess 120 125 130

61 communicates with a like recess 62 in the side of the rectangular opening 24, when said coin will drop through said opening 24 into the interior of the base portion 10 of the 5 device. As the carrier 26 travels forward it compresses the spring 45 against the roller bearings 43-43 and when it reaches the limit of its forward travel the openings 39 and 40 communicate whereby a ball 65 drops 10 therethrough into the chute 41 and is delivered to the operator through the opening 42 in the front of the base portion 10 of the device. It will be noted that the ball 65 is not delivered to the operator until the coin 15 60 has been released into the interior of the base 10. When the said carrier 26 reaches the limit of its forward travel and delivers the ball to the operator, as just described, and pressure on the thumb latch 46 is without 20 drawn, the compression on the spring 45 is released and the carrier 26 will return to its normal position in readiness for re-use. The thumb latch 46 will resume its normal position by reason of releasing the tension on the 25 spring 23. The device will deliver but one ball 65 to the chute 41, when the openings 39 and 40 coincide, as when the forward movement of the carrier 26 begins a ball 65 will drop in the opening 39 therein and as said 30 carrier 26 continues its forward travel the ball 65 is carried therewith beneath a ledge (vide Fig. 2) until said openings 39 and 40 coincide, when the ball 65 is delivered to the chute 41; said ledge preventing more than 35 the one ball 65 being delivered when said openings 39 and 40 coincide.

The operation of the ratchet 48 is as follows:—When the coin 60 is forced under the depression 63 the forward movement of the 40 carrier 26 to effectuate this result causes said ratchet 48 to engage the first of the ratchet teeth 49, preventing a return movement of the carrier 26 should the pressure of the cam 47 against the coin 60 be released. As 45 the pressure of the cam 47 against the coin 60 is continued to the point where said coin 60 is released into the interior of the base 10 as hereinbefore described, the continued forward movement of the carrier 26 50 in unison therewith causes the said ratchet 48 to engage the following ratchet tooth and the continued forward movement of the carrier 26 causes said ratchet 48 to engage the next ratchet tooth until said carrier 26 has 55 completed its forward travel when the said ratchet 48 is released from engagement with the teeth 49 and rests in a recess adjacent said teeth on the boss 27. These positions of the ratchet 48 are shown in detail in Figs. 2, 60 3 and 4 of the drawing. As the carrier 26 resumes its normal position by means of the pressure of the spring 44 being released the ratchet 48 will resume its normal position on the opposite side of the ratchet teeth 49, 65 the pressure of the fully compressed spring

44 being greater than that of the ratchet spring 50.

The foregoing described operation of the ratchet 48 prevents the operator from so manipulating the thumb latch 46 as to secure 70 more than one ball for his one coin and at the same time insures the operator of delivery of his ball by a continued pressure on the thumb latch 46.

If after a coin 60 is secured beneath the 75 depression 63 an additional coin is inserted in the device it will pass through the slots 36-37 and out the slot 38, the second coin not coming in contact with the shoulder of the ratchet 31.

Until a coin is inserted the initial forward movement of the carrier 26 cannot be effected as there must be a coin for the cam 47 to contact against to cause this initial movement.

In the forward movement of the carrier 26 the cam 47 rides upwardly on the coin 60 until at the point where the coin reaches the communicating recesses 61 and 62, said cam loses contact with said coin but contacts 90 sufficiently against the depression 63, by reason of the peculiar contour of said cam, to effect the full travel of the said carrier 26.

The plate 13 has a longitudinal opening therein for the travel of the carrier 26 and 95 to permit the balls 65 in the container 15 to reach the opening 39 in said carrier. This opening, as well as the opening 39, is preferably made sloping so that the balls may more readily drop therein.

Vertical stanchions or pins 46² (Fig. 7) and 64 are positioned on the carrier 26 and extend upwardly through the opening in the plate 13 into the container 15, so that as said carrier 26 travels to and fro said pins will 105 separate such balls as may stick together.

It will now be apparent that I have devised a novel and useful construction which embodies the features of advantage enumerated as desirable in the statement of the invention and the above description, and while I have in the present instance shown and described the preferred embodiment thereof which has been found in practice to give satisfactory and reliable results, it is to be understood that the same is susceptible of modification in various particulars without departing from the spirit and scope of the invention or sacrificing any of its advantages.

Having thus described my invention what I claim as new and desire to secure by Letters Patent is:—

1. In a coin controlled vending machine of the class described, a carrier under spring pressure, a boss beneath said carrier having downwardly extending lugs and being longitudinally slotted, a ratchet under spring pressure positioned in a recess in said boss beside one of the said lugs and extending 125

beyond the line of said lugs, said ratchet and said lugs forming a support for a coin when said coin is positioned against said lugs and the inner side of said ratchet, a cam lever 6 adapted for contact with said coin to cause a partial forward movement of said carrier, means for releasing said coin from contact with said lugs and said ratchet before said carrier completes its forward travel, said 10 carrier completing its forward travel by pressure of the cam lever thereagainst after said coin has been released, and means to deliver a predetermined portion of the contents of said machine upon the completion 15 of the forward travel of said carrier, substantially as described.

2. In a coin controlled vending machine, of the class described, a carrier under spring pressure, a boss beneath said carrier having 20 downwardly extending lugs and being longitudinally slotted, a ratchet under spring pressure positioned in a recess in said boss beside one of the said lugs and extending beyond the line of said lugs, said ratchet 25 and said lugs forming a support for a coin when said coin is positioned against said lugs and the inner side of said ratchet, a cam lever adapted for contact with said coin to cause a partial forward movement of said 30 carrier, means for releasing said coin from contact with said lugs and said ratchet before said carrier completes its forward travel, said carrier completing its forward travel by pressure of the cam lever there- 35 against after said coin has been released, means to prevent a return movement of said carrier until it completes its forward travel and means to deliver a predetermined portion of the contents of said machine upon 40 the completion of the forward travel of said carrier, substantially as described.

3. In a coin controlled vending machine of the class described, a carrier under spring pressure, means for retaining a coin in a 45 vertical position against said carrier, a recess in the under forward portion of said carrier, a cam lever adapted for contact with said coin, the pressure of said cam lever securing said coin in said recess and causing a 50 partial forward movement of said carrier, means for releasing said coin before said carrier completes its forward travel, said carrier completing its forward travel by pressure of said cam lever against said recess 55 in said carrier after said coin has been released and means to deliver a predetermined portion of the contents of said machine upon

the completion of the forward travel of said carrier, substantially as described.

4. In a coin controlled vending machine 60 of the class described, a carrier under spring pressure, a boss on the under side of said carrier, means for retaining a coin in a vertical position against said carrier, a cam lever adapted for contact with said coin to 65 cause a partial forward movement of said carrier, means for releasing said coin before said carrier completes its forward travel, said carrier completing its forward travel by pressure of said cam lever thereagainst after 70 said coin has been released, ratchet teeth on the opposite side of boss from said coin releasing means, a ratchet, under spring pressure, adapted to engage said ratchet teeth as said carrier moves forwardly until said carrier has completed its forward travel when 75 said ratchet is released from engagement with said ratchet teeth and means to deliver a predetermined portion of the contents of said machine upon the completion of the 80 forward travel of said carrier, substantially as described.

5. In a coin controlled vending machine 85 of the class described, a carrier under spring pressure, a boss on the under side of said carrier having downwardly extending lugs and being longitudinally slotted, a ratchet, under spring pressure, positioned in a recess in said boss beside one of the said lugs and extending beyond the line of said lugs, a 90 notch at the terminus of said ratchet to normally engage the end of the lug beside it, said ratchet and said lugs forming a support for a coin when said coin is positioned against said lugs and the inner side of said 95 ratchet, a cam lever adapted for contact with said coin to cause a partial forward movement of said carrier, said coin moving forward with said carrier gradually forcing the notched end of the ratchet out of engagement with the said lug, until said coin reaches a recess in said ratchet, communicating with a like recess in the body portion of the device, whereby the coin is released into the base of said device, said carrier completing its forward travel by pressure of the cam lever thereagainst after said coin has been released, and means to deliver a predetermined portion of the contents of said machine upon the completion of the forward travel of said carrier, substantially as described.

In testimony whereof I affix my signature.
WILLOUGHBY L. T. HAIN.
